UNITED STATES PATENT OFFICE

2,503,685

TOOL AND DRIVING MEMBER

Don H. Proctor, Springfield, Mass., assignor to
 Lovejoy Tool Company, Inc., Springfield, Vt.,
 a corporation of Vermont

Application January 2, 1947, Serial No. 719,683

3-Claims. (Cl. 276—76)

1

This invention relates to tools such as end mills, or the like, and adapters or other driving members, and has for an object to provide a construction whereby tools of different types and sizes may be readily interchanged and which when in position are firmly fixed and are positively driven from the driving member.

For a complete understanding of this invention, reference may be had to the accompanying drawings in which

Figure 1 is a side elevation partly broken away and in section of an adapter to which an end mill is secured and embodying the invention.

Figure 2 is a front end elevation of the same.

Figure 3 is an exploded perspective view of the mill and the elements for securing it in the adapter.

Referring to the drawings, at 1 is indicated an adapter having a tapered portion 2 arranged to be engaged in a matingly tapered opening of a rotary spindle, or the like, in accordance with usual practice, to be driven by frictional engagement between the mating tapered faces. Coaxial with the rotational axis of the adapter 1 it is provided with a tubular socket 3 extending inwardly from its larger end. This socket 3, shown as non-tapered, may receive the shank of a tool which is to be supported in driven relation to the adapter 1. As shown the tool is an end mill 4 having suitable cutting edges thereon, the shank portion 5, as shown best in Figures 1 and 3, being generally cylindrical in outline and of a size to mate the socket 3 of the adapter. One side of the shank 5, however, is cut away to form a laterally flat face 6 which leaves a space between this flat face and the opposite interior face of the socket 3 and within this space may be placed a segmental element 7. This segmental element 7 and the shank 5 have their mating faces formed with interfitting serrations 8 which permit the element 7 to be associated with the shank of the tool in a multiplicity of axial positions, adjacent positions differing from each other by small increments of a size depending upon the size of the serrations 8. When the segmental element 7 is assembled with the shank, the two together may be inserted in the socket 3, substantially filling this socket. The segmental element 7 is provided in its convex face with a notch 9 presenting a flat transverse face 10 at its base, this notch being of sufficient width to receive therein a key 11. This key is segmental in shape and has a longitudinally tapered flat face 12 which may be engaged with the flat face 10 of the element 7.

The key 11 fits in a transverse bore or passage

2

14 through the adapter 1, this transverse bore being offset axially from the axis of the socket 3 but intersecting the same as clearly shown in Figure 2. This passage 14, as shown, is of cylindrical outline, mating the curvature of the curved face of the key 10, so that when the tool shank 5 with the segment 7 associated therewith has been inserted in the socket 3 to the proper depth, the notch 9 of the segment is in position to receive 10 therein the side edges of the key 11 and as this key 11 is pushed into position with its smaller end pushed through the passage 14, the element 7 and the shank 5 of the tool are clamped firmly in position in the socket 3, but they may be released 15 readily by inserting a suitable tool against the small end of the key 11 and driving the key out from the passage 14, releasing the tool shank and the element 7 for removal.

Not only does this construction afford a readily 20 removable locking means for retaining the tool shank in position, but the bearing of the key 11 against the flat base 10 of the notch 9 and the engagement of the opposite face of the element 7 against the transversely flat face of the shank 15 provides a positive driving connection between the adapter 1 and the tool.

From the foregoing description of an embodiment 30 of this invention, it should be evident to those skilled in the art that various changes and modifications might be made without departing from its spirit or scope.

I claim:

1. The combination with a rotary driving member having a socket therein and an opening transverse of and intersecting said socket, of a tool having a shank for insertion in said socket, said shank having a transverse wall member, and a key arranged transverse to the rotational axis of said member operatively engaging said transverse wall member and seated in said opening, holding said shank in said socket and acting as constituting therewith a rotary driving connection between said member and tool.
2. The combination with a rotary driving member having a tubular socket coaxial with the rotational axis of said member and a lateral passage intersecting said socket, of a rotary tool provided with a shank having a portion fitting said socket and a portion spaced from the wall of said socket, an element substantially fitting said space, said element and shank having confronting faces providing for assembly of said element with said shank in multiplicity of axial interfitting relations, said element having a transverse notch,

and a key arranged transverse to the rotational axis of said member engageable in said passage and in said notch acting to retain said shank and element in said socket and constituting there-with a driving connection between said member and tool.

3. The combination with a rotary driving member having a tubular socket arranged coaxial with its rotary axis and a transverse tubular passage offset from the axis of said socket but intersecting said socket, of a tool having a shank portion for engagement in said socket, said shank portion being provided with a laterally flat face, an element engageable with said flat face and with said shank substantially filling the cross sectional area of said socket, the mating faces of said shank and element having interfitting serrations permitting assembly of said element and shank in a multiplicity of rela-

tive axial positions, said element having a transverse notch therein, and a key arranged transverse to the rotational axis of said member having a longitudinally tapered face engaging in said notch and slidably fitting in said transverse passage for retaining said element and shank assembled in said socket and constituting there-with a positive driving connection between said member and tool.

Certificate of Correction

Patent No. 2,503,685

April 11, 1950

DON H. PROCTOR

It is hereby certified that error appears in the printed specification of the above numbered patent requiring correction as follows:

Column 2, line 42, strike out the words "acting as";
and that the said Letters Patent should be read with this correction therein that the same may conform to the record of the case in the Patent Office.

Signed and sealed this 11th day of July, A. D. 1950.
